UNITED STATES PATENT OFFICE.

THOMAS W. MORGAN, OF WATERLOO, IOWA, ASSIGNOR TO WILBUR W. MARSH, OF WATERLOO, IOWA.

VALVE-TIMER FOR INTERNAL-COMBUSTION ENGINES.

1,150,291.

Specification of Letters Patent.

Patented Aug. 17, 1915.

Application filed December 30, 1912. Serial No. 739,193.

To all whom it may concern:

Be it known that I, THOMAS W. MORGAN, a citizen of the United States, and a resident of Waterloo, in the county of Blackhawk and State of Iowa, have invented certain new and useful Improvements in Valve-Timers for Internal-Combustion Engines, of which the following is a full, clear, and exact specification.

10 My invention relates to internal combustion engines, and has more particular reference to improvements in valve timers therefor.

15 The primary object of my invention is to provide an improved valve timer for reversible internal combustion engines.

20 A further object of my invention is to provide an improved mechanism of this character which will be simple, durable and reliable in construction, inexpensive to manufacture, and effective and efficient in operation.

25 Other objects of my invention will appear hereinafter.

30 My invention consists in the features of novelty exemplified in the construction, combination and arrangement of parts herein described, and shown in the accompanying drawings which illustrate one embodiment of my invention, and more particularly pointed out in the appended claims.

35 In the drawings, Figure 1 is an end elevation of a single cylinder internal combustion engine embodying my invention. Fig. 2 is a view of said engine in elevation at right angles to that of Fig. 1. Fig. 3 is an enlarged elevation of the cam and gear mechanism. Fig. 4 is a sectional view on the line 4—4 of Fig. 3. Fig. 5 is a fragmentary section on line 5—5 of Fig. 3. Fig. 6 is a view of the cams and valve actuating mechanism embodying my invention as applied to a four-cylinder engine; and Fig. 7 is a 45 lefthand end view of the mechanism shown in Fig. 6.

40 My invention concerns more particularly to the valve timing and operating mechanism of internal combustion engines, and 50 for the sake of simplicity of illustration, I have shown in the drawings a single cylinder engine of the type in which only the exhaust valve mechanism is operated by cams driven from the crank shaft. It will be ob-

55 vious, however, to one skilled in the art, after having obtained an understanding of my invention from the disclosures herein made, that my invention may, without departing from the scope and spirit thereof, be applied to other types of internal combustion engines, such for instance, as the type wherein both the exhaust and intake valves are cam-operated.

60 The engine shown in the drawings may be of the usual or standard type having an explosion cylinder A in which a piston (not shown) operates to drive the crank shaft A¹ by means of the usual connecting rod which is inclosed within the crank case A². On the crank shaft a balancing fly wheel A³ is generally provided. I have not thought it necessary to illustrate the details of that portion of the valves which lie within the cylinder A, nor the intake or exhaust passages by which the gas is conveyed to the 75 cylinder and the exhaust conveyed therefrom for the reason that these parts and mechanisms may be of any usual or standard construction well known in the art. Suffice to say that the rod 1 which reciprocates vertically in the bearing 2 on the head of the cylinder in the usual way is representative of the valve mechanism of internal combustion engines. The rod 1 moves vertically downward in its bearing as is well 80 known to open the exhaust port and allow the escape of exhaust gases and moves upward in its bearing to close said port. These rods, in engines of the type of which that shown in the drawing is representative, are 85 constantly pressed upward by the spring 3 to hold the exhaust port closed, spring 3 being disposed between the head of the cylinder and a collar 4 on the rod. At the proper time for the port to be opened the walking beam 5 is operated to depress the rod 1 against the action of its spring 3. This walking beam may be of the type used in connection with single cylinder internal combustion engines. It consists of a sub- 90 stantially horizontally disposed lever centrally pivoted upon an upstanding lug 6 cast on the cylinder head, as shown clearly in Figs. 1, 2, 8 and 9. The arm 7 of this walking beam is arranged in position to act 95 upon the upper end of the rod 1 and depress it at the proper time. A screw member 8 is generally provided for adjusting the 100

105

relation of the arm 7 and the rod 1. The other arm 9 of the walking beam overhangs the cylinder in position to be engaged by the upper end 10 of the valve actuating rod or member 11 in the usual way. In the structure shown in the drawings this actuating rod 11 is mounted to reciprocate vertically in bearings 12 on the side of the cylinder. The engine shown, as before stated, is representative of the standard single cylinder engines now on the market and in this type of engine the make-and-break sparking apparatus 14 is positioned in such relation to the valve actuating rod 11 that it may be actuated thereby, an arm 15 being mounted upon the member 11 for this purpose. As is well known these mechanisms are so timed in relation to each other that the spark will occur at proper intervals. The sparking apparatus needs no further explanation.

It is generally well known that internal combustion engines may be run in either direction of rotation, depending upon the direction in which they are initially started.

25 The opening and closing of the valve, however, must bear a definite time relation to the operation of the engine. In other words, the valves open and close at certain points in the cycle of operation of the piston and 30 these points, as is well known, change in accordance with the direction of rotation of the engine. In accordance with my invention I provide valve timing mechanism which times the valves properly 35 relatively to the direction in which it is desired to run the engine without the necessity of having to disassemble and re-assemble the parts or mechanism.

40 As a simple way of carrying out my invention, I provide a pinion spur gear 20 on the crank shaft A^2 , which gear is arranged to drive a larger spur gear 21 mounted upon a suitable stud shaft 22 projecting from the side of the crank case A^2 of the engine. The

45 centers of the crank shaft A^1 , stud shaft A^2 and the valve actuating member 11 being preferably positioned in vertical alinement. The large gear 21 is free to rotate on the stud shaft. Adjacent one face of the large

50 gear 21 I provide a cam 23. This cam is rotatably mounted upon the hub of the gear 21, as shown in Figs. 4 and 5, so that both cam and gear may be independently rotated. The cam 23 when it rotates, reciprocates the

55 valve actuating member 11. The lower end of the member 11 carries a small anti-friction roller 25 which engages and runs on the surface of the cam 23. During the operation of the engine it will be seen that the

60 cam 23 must occupy such a position relatively to the piston of the engine that the exhaust valve will be operated at the proper time. The relative position of the cam for one direction of rotation of the engine will

65 not, as is readily seen, serve for the other

direction of rotation and consequently the cam must be relatively shifted, and for this reason, as before intimated, the cam may be rotated relatively to the gear 21. Since, however, the cam after being rotatively shifted to its proper position must be maintained in position I provide a connection between the gear 21 and the cam which permits of these conditions. In the structure shown this connection is preferably formed by two small spring pressed pins 30 projecting from the inner face 31 of the cam and adapted to enter small depressions in the adjacent face of the large gear 21. These small pins are preferably hollow (Figs. 3, 4, 5 and 6) for the reception of the small spiral springs 32. The pins are mounted to slide in suitable bores or holes in the face of the cam 21. The springs 32 are held in place by the removable screw caps 35 and tend to yieldingly force the members or pins 33 against the face of the gear 21. The ends of these pins are preferably cone-shaped so that when a certain amount of relative rotative force is applied to the cam the small pins will yield and ride out of the depressions in the face of the gear 21. I provide two sets of depressions 36 for the spring pressed pins. The two depressions in each set are placed in the proper relative position corresponding to the directions of rotation of the engine. For instance: in Figs. 1 and 3 the cam is shown in the proper relative position corresponding to the direction of rotation of the crank shaft indicated by the arrow X (Fig. 1), while the dotted outline (Fig. 1) of the cam shows it in proper position corresponding to the direction of rotation of the crank shaft indicated by the arrow Y. It will thus be seen that by simply shifting the cam rotatably a slight amount it may be conveniently and properly positioned to actuate the valve member 11 and the valve mechanism in proper timed relation to the other parts of the engine depending upon the direction of rotation of the engine. This cam, if desired, may be shifted manually before the engine is started, but I prefer that this operation take place automatically. For this reason I so proportion the parts that during the initial movement of the crank shaft and larger gear in either direction of rotation the cam will be automatically shifted to the proper position corresponding to that direction of rotation, and the engine may be run continually in that direction without any further necessity of adjusting the cam or other operating part. This automatic operation may be simply accomplished by arranging the valve actuating member 11 and the other parts of the valve mechanism in such manner that they will offer sufficient resistance to the turning of the cam to shift it from one set of depressions to the other. In order, however,

to prevent further relative rotation of the cam after it has been properly shifted, as above described, I provide a curved slot 38 in the large gear 21. In this slot a bolt 39 is adapted to operate. This bolt is, as shown in Fig. 5, inserted through a slot in the gear and screwed into the cam 23. The ends of the slot, co-acting with the bolt, serve as limit stops corresponding to the two positions of the cam, and hence after the cam has been shifted from one of its positions to the other the bolt and slot prevent further rotation thereof during the continuous operation of the engine. This bolt also is intended to serve as a locking means for locking the cam and gear together in the event that it is desired to run the engine for any extended length of time in one direction. In other words, after the cam has been shifted either automatically or manually, as the case may be, to the position corresponding to the direction of rotation of the engine, the bolt may be tightened to clamp the cam firmly to the gear, and the engine may then be started and stopped as many times as desired without danger of the adjustment being disturbed.

As before intimated, my invention is equally as applicable to two or four cylinder engines, or engines embodying commercially practicable number of cylinders, and in order that this may be clearly understood, I have illustrated my invention as applied to a four cylinder engine. I consider it unnecessary to illustrate a complete engine in this connection and for this reason I have, in Figs. 6 and 7, illustrated a portion of the crank shaft and the cam shaft together with the interconnected driving mechanism. In this construction the cam shaft is considerably longer than the cam shaft 22 for the single cylinder engine, so that it may extend in operative relation to the valve actuating members 11 of the several cylinders. This shaft carries four cams 23¹ angularly arranged around the cam shaft 22 so as to operate the valve rods 11 in their proper sequence. It would be impracticable and inconvenient, although possible, to provide a cam and gear connection for each of the valve actuating members 11, and for this reason I provide a common arm or member 45 adjacent the gear 21. This arm is keyed or otherwise securely fastened to the cam shaft 22 but the gear 21 is rotatable thereon. Only one spring pressed pin 32 instead of two as in Fig. 1, is necessary, hence it is only necessary to provide one depression 36 for each of the two relative positions of the arm 45 with respect to the direction of rotation of the parts. The arm 45 has a similar bolt and slot connection 39 and 38 respectively, with the large gear. This construction performs the same functions as previously described in connection with the

single cylinder engine. Thus the four cams can be automatically positioned as a group with respect to the direction of rotation instead of an individual mechanism for each of the four cams.

It will thus be seen that my invention provides a very simple and effective means for timing the valve mechanism with respect to the direction of rotation. When the mechanism is arranged to operate automatically, as previously described, the initial movement of the parts in either direction when cranking the engine automatically shifts the cams and times them with respect to the particular direction of rotation of the engine, and no further manipulation or adjustment is required. The engine may then continue to operate in that direction of rotation with its valve mechanism correspondingly timed. When it is to be reversed, the act of cranking in the reverse direction automatically shifts the cam accordingly.

What I claim is:

1. The combination with the cam shaft of an internal combustion motor, of a gear wheel mounted thereon and driven from the engine shaft, said gear wheel being provided with an arcuate slot concentric to the cam shaft, a cam journaled on the shaft at one side of said gear wheel, a pin on said cam movable lengthwise of said slot, a locking dog for holding the cam with its said pin at either end of the slot, and a spring for yieldingly maintaining the said locking dog and cam in holding position.

2. The combination with a cam shaft of an internal combustion motor, of a gear wheel mounted thereon and driven from the engine shaft, said gear wheel being provided with an arcuate slot concentric to the cam shaft, a cam journaled on the cam shaft in proximity to one side of said gear wheel, a pin mounted on said cam engaging said slot, and a locking dog holding said pin at either end of the slot.

3. The combination with a cam shaft of an internal combustion motor, of a gear wheel mounted thereon and driven from the engine shaft, said gear wheel being provided with an arcuate slot concentric to the cam shaft, a cam journaled on the cam shaft proximate to the side of the gear wheel, a pin mounted on said cam for engaging said slot, a locking means for holding said pin at either end of said slot, and a spring for pressing the locking means into engaging position.

4. The combination of a cam shaft, a gear journaled on said shaft and having an arcuate slot, a cam secured to said shaft and positioned adjacent said gear, a pin on said cam extending into said slot, said gear also having a pair of depressions in its face corresponding to the relative position of the pin in said arcuate slot, and spring-pressed

dogs carried by said cam adapted to engage said depressions and yieldingly hold the cam with its pin at either end of the slot.

5. The combination with a shaft, of two relatively rotatable elements on said shaft in position adjacent each other, one of said elements having an arcuate slot and the other a pin playing in said slot, a spring-pressed dog projecting from the face of one of said 10 elements, and a pair of depressions in the adjacent face of the other element corresponding to the relative positions of the

elements with the pin at the ends of the slot and adapted to be engaged by said spring-pressed dog to hold the said pin in the corresponding end of the slot. 15

In testimony whereof I have signed my name to this specification, in the presence of two subscribing witnesses, on this 27th day of December A. D. 1912.

THOMAS W. MORGAN.
